(57) **CLAIM**

The ornamental design for a key for a water filter assembly, as shown and described.

DESCRIPTION

FIG. 1 is a top perspective view of a portion of a key for a water filter assembly;

FIG. 2 is a top plan view thereof;

FIG. 3 is a front elevation view thereof, the rear view being a mirror image of same;

FIG. 4 is a left side elevation view thereof; and,

FIG. 5 is a right side elevation view thereof.

The subject matter shown in broken lines is not considered part of the claimed design.
